UNITED STATES PATENT OFFICE.

LEWIS L. SCOTT, OF ST. LOUIS, MISSOURI, ASSIGNOR TO STANDARD ENGINEERING COMPANY, OF ST. LOUIS, MISSOURI, A CORPORATION.

COMBUSTION SYSTEM.

1,352,227.

Specification of Letters Patent. Patented Sept. 7, 1920.

Application filed March 6, 1918. Serial No. 220,856.

To all whom it may concern:

Be it known that I, LEWIS L. SCOTT, a citizen of the United States, residing in the city of St. Louis, Missouri, have invented a new and useful Improved Combustion System, of which the following is a specification.

My invention relates to the burning of heavy oils which are practically nonvolatile at normal temperature, and concerns a combustion system whereby heavy oils are ignited at normal temperature by an electric spark.

My invention can be used in connection with any heat absorbing medium such, for example, as a steam generator used in steam automobiles.

Heavy liquid hydrocarbon, such as kerosene, can be completely burned without pre-heating, at normal temperature by finely dividing the liquid fuel and mixing it with the proper amount of air to support combustion. A completely combustible mixture of heavy hydrocarbon and air at normal temperature, however, cannot be ignited by an electric spark of normal size, and in order to ignite a finely divided fuel mixture by said spark, it is necessary that the mixture be rich in hydrocarbon and, therefore, incompletely combustible, so that it is necessary to add air to said rich mixture in order to get complete combustion.

One object of my invention is to provide an inexpensive, simple and effective combustion system that will generate a great amount of heat and that will burn heavy hydrocarbon fuel and ignite same by an electric spark without any preheating. To this end, I employ a plurality of liquid fuel atomizers which produce finely divided mixtures of hydrocarbon fuel and air, and the mixture from at least one of said atomizers being ignited by means of an electric spark; and to the mixtures from these atomizers I furnish additional air so as to get complete combustion. I also provide means for bringing all of said mixtures into operation in substantial unison.

Another object of the invention is to automatically control the operation of the system by changes in a heat absorbing medium, such as a steam generator.

In the accompanying drawings:

Figure 1 is a diagrammatic view of my

combustion system as applied to a steam generator;

Fig. 2 is an end view of the fuel atomizers and electric driven blower used in connection with my combustion system; and

Fig. 3 illustrates a form of fuel atomizing nozzle that may be used in connection with my combustion system.

Referring to the drawings, the numeral 1 indicates the coils of a steam generator of the semi-flash type, 2 the water inlet to the coils and 3 the steam outlet pipe. Inclosing the coils is a heat insulating casing 4 which has a combustion chamber 5 formed in its lower portion. The numeral 6 indicates an air compressor, which is provided with the usual check valves 7. This air compressor may be driven in any suitable manner, as by a steam engine or an electric motor, neither of which is shown. The numeral 8 indicates an air tank for storing air at high pressure from the air compressor 6 and is provided with a small hand-operated air pump 9. Leading from the air tank 8 is a delivery pipe 11 which is provided with a common reducing valve 10, the purpose of which is to reduce the air pressure from the tank 8 to the delivery pipe and keep the air pressure in said pipe constant.

The numeral 12 indicates a kerosene fuel tank. Connected to the pipe 11 is an air pipe 13 which communicates with the fuel tank 12 at the top thereof and is provided with a valve 14. The numeral 15 indicates an air pipe which is also connected to the delivery pipe 11 and leads to the air nozzles 16, 17 and 18, Fig. 2. The pipe 15 is provided with a valve 19 which is adapted to be opened by the solenoid 20, the action of which will be described later. Leading from the bottom of the fuel tank 12 is a pipe 21 which is connected to a float valve 22. Leading from the float valve 22 is a fuel pipe 23 which is connected to the fuel nozzles 24, 25 and 26, Fig. 2. Air from the nozzles 16, 17 and 18 atomizes fuel from the nozzles 24, 25 and 26, respectively, and said atomized mixtures, which are rich in hydrocarbon are directed toward the combustion chamber 5 by the mixture nozzles 27, 28 and 29, respectively. A spark plug 30 is placed in cooperation with one or more of the mixture nozzles. In the drawing it is shown as

operating with the nozzle 28 only. Electric current for the spark plug is furnished from the battery 31 through a common spark coil of which 32 is the primary winding and 33 the secondary winding.

The numeral 34 indicates an electric motor which drives an air blower 35, which blower forces additional atmospheric air to the combustion chamber 5 through a pipe or duct 36 which pipe incloses in common the mixture nozzles 27, 28 and 29, to complete combustion of the mixtures from said mixture nozzles and project the flame onto the coils 1. The numeral 37 indicates a manually operated switch connecting the negative side of the battery 31 to the solenoid 20 through the wire 38. A wire 39 connects one terminal of the solenoid to one side of the motor 34. Connected to the other side of the motor is a wire 40 which at its outer end is connected to a stationary insulated contact screw 41. The numeral 42 indicates a Bourdon tube which is in communication with the steam pressure in the generator coil 1 through the medium of a pipe 43. When a predetermined pressure is created in said Bourdon tube it will move a spring-held lever 44 out of contact with the screw 41. A wire 45 connects the positive side of the battery 31 to the lever 44, and when this lever is moved by the Bourdon tube out of contact with the screw 41, the electric circuit will be broken. When this occurs, the motor 34 will not operate and the solenoid operated valve 19 will remain closed so that no air can flow to the nozzles 16, 17 and 18, and, therefore, no fuel will be atomized and forced into the combustion chamber. It will also be noted that the primary winding 32 of the spark coil 40 is connected in parallel with the wire 45 which leads to the lever 44, so that when the electric circuit is opened by the action of the Bourdon tube 42, the current to the spark coil is cut off in unison with the current to the motor 24 and solenoid 20.

In Fig. 3 I have shown an air nozzle 46 and a fuel nozzle 47 entering a relatively flat mixture nozzle 48 which is triangular in shape, the air and fuel nozzles entering near the pointed end of the mixture nozzle. The latter provides an outwardly flaring mixture chamber 49 terminating in a narrow elongated outlet 50. This form of mixture nozzle is intended to provide an intimate mixture of the air and fuel and a wide distribution in a thin sheet of the ignited fuel through the outlet 50.

I claim:-

1. A hydrocarbon burner comprising a plurality of liquid fuel spraying and mixture forming atomizers, an ignition device co-operating directly with one of said atomizers, and means for forcing additional atmospheric air into the mixtures from all

of said atomizers after the ignition of the mixture in one of said atomizers by said ignition device.

2. A hydrocarbon burner comprising a plurality of liquid fuel spraying and mixture forming atomizers, an ignition device for igniting the mixture from one of said atomizers, an air duct surrounding all of said atomizers, and means for forcing atmospheric air into said duct to combine with the mixtures from all of said atomizers. 75

3. In a combustion system, the combination with a heat absorbing medium of a liquid fuel spraying and mixture forming atomizer, means for forcing additional atmospheric air into the mixture from said atomizer, and means responsive to changes in conditions in the heat absorbing medium for automatically controlling the fuel mixture from said atomizer and said additional air supply. 85

4. In a combustion system, the combination with a heat absorbing medium of a liquid fuel spraying and mixture forming atomizer, an ignition device for igniting the mixture from said atomizer, means for forcing additional atmospheric air to the mixture from said atomizer, and means responsive to changes in conditions in the heat absorbing medium for automatically controlling the fuel mixture from said atomizer, the additional air supply and the ignition device in substantial unison. 90

5. In a combustion system, the combination with a heat absorbing medium of a liquid fuel spraying and mixture forming atomizer, an ignition device for igniting the mixture from said atomizer, means for forcing additional atmospheric air to the ignited mixture from the atomizer, an electric device for controlling the atomizer, an electric device for controlling the additional air supply, a source of electricity for furnishing electric current to said electric devices, and means responsive to changes in conditions in the heat absorbing medium for automatically making and breaking the electric circuit. 100

6. In a combustion system, the combination with a heat absorbing medium of a liquid fuel spraying and mixture forming atomizer, an ignition device for igniting the mixture from said atomizer, means for furnishing additional air to the ignited mixture from the atomizer which comprises an air blower and an electric motor for driving the same, a solenoid valve for controlling the operation of the atomizer, a source of electricity for furnishing electric current to said motor and said solenoid valve, and means responsive to changes in conditions in the heat absorbing medium for automatically making and breaking the electric circuit. 115 120 125

7. In a combustion system, the combination with a heat absorbing medium of a liquid fuel spraying and mixture forming atomizer, an electric ignition device for igniting said mixture in the atomizer, means for forcing additional atmospheric air to the ignited mixture from the atomizer, an electric device for controlling the atomizer, an electric device for controlling the additional air supply, a source of electricity for furnishing electric current to said electric devices, and means responsive to changes in conditions in the heat absorbing medium for automatically making and breaking the electric circuit.

8. In a combustion system, the combination with a heat absorbing medium, of a liquid fuel spraying and mixture forming atomizer, an ignition device for igniting said mixture from said atomizer, means for furnishing additional air to the ignited mixture, a storage tank, an air compressor for furnishing high pressure air thereto, a connection from said air storage tank to the atomizer, a pressure reducing valve located in connection, an electric device controlling the operation of the atomizer, an electric device for controlling the operation of the additional air supply, a source of electricity for furnishing electric current to said electric devices, and means responsive to changes in conditions in the heat absorbing

medium for automatically making and breaking the electric circuit.

9. In a combustion system, the combination with a heat absorbing medium, of a plurality of liquid fuel spraying and mixture forming atomizers, an ignition device for igniting the mixture from one of said atomizers, an air duct common to all of said atomizers, and means for forcing additional atmospheric air through said duct and into the mixture from the atomizers.

10. In a combustion system, the combination with a heat absorbing medium, of a plurality of liquid fuel spraying and mixture forming atomizers, an ignition device for igniting the mixture from one of said atomizers, an air duct common to all of said atomizers, means for forcing additional atmospheric air through said air duct and into the mixture from said atomizers, and means responsive to changes in conditions in the heat absorbing medium for automatically controlling the fuel mixture from said atomizers, the additional atmospheric air and the ignition device in substantial unison.

In witness whereof I have hereunto set my hand this 3rd day of March 1918.

LEWIS L. SCOTT.
